UNITED STATES PATENT OFFICE.

FRANCIS C. GERBASI, OF BROOKLYN, NEW YORK, ASSIGNOR TO GERBASI MANUFACTURING COMPANY, INC., OF NEW YORK, N. Y., A CORPORATION OF NEW YORK.

DESIGN FOR A LADY'S BELT.

56,659.

Specification for Design.

Patented Nov. 23, 1920.

Application filed July 3, 1920. Serial No. 393,981. Term of patent 7 years.

To all whom it may concern:

Be it known that I, FRANCIS C. GERBASI, a subject of the King of Italy, residing at Brooklyn, in the county of Kings and State of New York, have invented a new, original, and ornamental Design for a Lady's Belt, of which the following is a specification, reference being had to the accompanying drawing, forming part thereof.

Fig. 2, is a perspective view in elevation of the locking ends of the belt drawn to a larger scale, to bring out more distinctly the design and stitching used.

I claim:

The ornamental design for a lady's belt, as shown.

FRANCIS C. GERBASI.
